BOAT STERN LIGHT

Clifford Brooks Stevens, Milwaukee, Wis., assignor to
The Vollrath Co., Sheboygan, Wis., a corporation of
Wisconsin

Application December 12, 1957, Serial No. 48,875

Term of patent 7 years

(Cl. D48—20)

Fig. 1 is a perspective view of a boat stern light, showing my new design, as seen from one side thereof, the opposite side of the boat stern light being the same in appearance as the side shown;

Fig. 2 is an enlarged fragmentary sectional view of the base position taken on line 2—2 of Fig. 1; and

Fig. 3 is a perspective view thereof as seen from the left and side of Fig. 1 with the standard fragmentarily shown for convenience of illustration only.

I claim:

The ornamental design for a boat stern light, substantially as shown and described.
